PAGE 2

Fig. 1 is a side elevational view of a trailer body showing my new design.

Fig. 2 also is a side elevational view opposite that shown in Fig. 1, and in a slightly reduced scale.

Fig. 3 is a rear elevational view of said body.

Fig. 4 is a front elevational view of said body.

Fig. 5 is a top plan view on a slightly reduced scale.

Fig. 6 is a side elevational view with the roof extensions and the counter elements in folded position.

Fig. 7 is a side elevational view, on a slightly reduced scale, similar to Fig. 2 with the roof extensions in folded position.

Fig. 8 is a rear elevational view similar to Fig. 3 except that the roof extensions and counter element are folded.

Fig. 9 is a front elevational view similar to Fig. 4 except that the roof extensions and counter element are folded.

Fig. 10 is a top plan view, on a slightly reduced scale, similar to Fig. 5 except that the roof extensions and counter element are folded.

The wheels, mast and hitch member shown by means of broken lines are disclosed only for illustrative purposes.

I claim:

The ornamental design for a trailer body, as shown and described.
